UNITED STATES PATENT OFFICE.

HJALMER B. HELSING, OF MOBERLY, MISSOURI.

DRAIN-DITCH CHECK DEVICE.

Application filed October 12, 1927. Serial No. 225,695.

The object of my invention is to provide a drain ditch check device of simple, durable, and comparatively simple construction.

A further object of my invention is to provide a device of this character adapted to be positioned in a drain ditch for the purpose of preventing the bottom of the ditch washing away during rainy weather.

Still a further object is to provide such a device consisting of a bottom and side portions adapted to rest on the bottom and sides of a drain ditch with anchoring means extending into the earth for the purpose of securely holding the device in position in the drain ditch.

Still a further object is to provide in connection with the bottom and the side walls, a front wall adapted to be filled with earth and to have the water which flows over this filling to fall over the wall and on the other side thereof.

Still a further object is to provide a splash board on the other side of the wall to catch the water which flows over the wall.

With these and other objects in view, my invention consists in the construction, arrangement and combination of the various parts of my invention, whereby the objects contemplated are attained, as hereinafter more fully set forth, pointed out in my claims, and illustrated in the accompanying drawing, in which:

Figure 1 is a perspective view of my improved drain ditch check device.

Figure 2 is a similar perspective view looking at the opposite side of the device.

Figure 3 is a layout view of a sheet of metal which is used to form the major portion of my device.

Figure 4 is a cross section through a drain ditch showing my device installed for use; and

Figure 5 is a sectional view through two of the devices and through the bottom of a drain ditch as taken on the indicated line 5-5 of Figure 4.

My device comprises a bottom member 10 having a downwardly extending anchoring portion 12 at one of its ends and an upwardly extending check wall portion 14 at its other end. Extending from the sides of the bottom portion 10 are side walls 16 provided with downwardly extending anchorage aprons 18 and upwardly extending check wall portions 20. The walls 16 extend upwardly and outwardly from the sides of the bottom portion

10 so that they may rest on the sides 22 of a ditch A as illustrated in Figure 4 of the drawings. In Figure 4, the reference numeral 24 indicates a highway and the ditch A is the usual drain ditch to be found along each side of an ordinary highway.

The wall portions 20 are secured to the wall portion 14 by bolts 26 extending through openings 28 in the wall portion 14 and through slots 30 in the wall portions 20. This construction allows the side walls 16 to be adjusted to different angles in order to fit different shaped ditches and after being so adjusted the bolts 26 are tightened in order to hold the parts in proper relation to each other.

A suitable brace 32 is provided to prevent bending of the wall portions 14 and 20 with relation to the bottom portion 10 and the side walls 16 of the device. The side walls 20 have forwardly bent portions 34 whereby the edge of the upper wall portions 20 slope from a highest point at the outer edge of the walls 16 down to the center check wall portion 14. The flanges 34 are bent up slightly, the purpose of which will hereinafter be more fully described.

Secured to the under side of the bottom portion 10 is a splash board 36 forming a continuation of the bottom portion 10 on the outside of the check wall portions 14 and 20. The splash board 36 is a separate piece of sheet metal which may be either riveted or bolted to the bottom portion 10 of my device.

In the use of my device, it is positioned in the ditch A as clearly shown in Figure 4 of the drawings. The anchoring aprons 12 and 18 extend down into the earth 38 as illustrated in dotted lines.

My devices are positioned at intervals along the ditch A as illustrated in Figure 5. The normal inclination of the ditch A is indicated by the dotted line 40 and when my devices are installed, the pocket formed by the bottom 10, sides 16, and walls 14 and 20, is filled with earth. After water has been travelling down the ditch A as indicated by the arrows 42, the ditch A behind my device fills up practically level as indicated at 44. This considerably lessens the speed of the water travelling down the ditch and thereby decreases its carrying power. The beneficial effect of this arrangement is to prevent to a great extent washing away of the earth 38 from the ditch A.

The portions 34 of the walls 20 tend to di-

rect the flowing water toward the center of the device and onto the splash board 36. The splash board 36 is provided to prevent washing away of the earth 38 immediately in front of the check device and to prevent undermining of the device which would cause it to become loosened from its position.

Some changes may be made in the construction and arrangement of the various parts of my invention, without departing from the real spirit and purpose of my invention, and it is my intention to cover by my claims, any modified forms of structure or use of mechanical equivalents, which may be reasonably included within their scope.

I claim as my invention:

1. A device of the class described comprising a bottom, sides extending therefrom, a front wall comprising a central portion extending up from said bottom and side portions extending up from said sides, said side portions being bent to make the center portion lower than the outer ends of the side portions and a splash board secured to said device.

2. A device of the class described comprising a bottom, sides extending upwardly and outwardly therefrom, a front wall comprising a central portion extending up from said bottom and side portions extending up from said sides, the upper edges of said

side portions being inclined to make the center portion lower than the outer ends of the side portions and a splash board forming, beyond said wall, a continuation of the bottom of said device. 35

3. A device of the class described comprising a bottom, sides extending upwardly and outwardly therefrom, anchoring means 40 comprising downwardly extending portions of said bottom and sides, a front wall comprising a central portion extending up from said bottom and side portions extending up from said sides, said side portions being 45 bent to make the center portion lower than the outer ends of the side portions and a splash board forming, beyond said wall, a continuation of the bottom of said device.

4. A drain ditch check device comprising a bottom portion, an upwardly extending front wall at one end thereof and an anchoring extension on the other end thereof, side walls connected to the sides of said bottom portion and bent upwardly at an angle to 55 the bottom portion, front walls on said side walls and forming a continuation of the front wall of said bottom portion, means for connecting said front walls together, portions of the front walls of said side portion 60 being bent so that the top edge of said walls slope toward the center front wall.

HJALMER B. HELSING.
